UNITED STATES PATENT OFFICE

2,535,733

PRINTING DEVICE

Walter T. Gollwitzer, Euclid, Ohio, assignor to
Addressograph-Multigraph Corporation, Wil-
mington, Del., a corporation of Delaware

Application May 31, 1946, Serial No. 673,670

2 Claims. (Cl. 129—16.3)

1

This invention relates to printing devices of the kind comprising a frame on which a printing plate and an index card are detachably retained. The invention pertains more particularly to an improvement in index cards used in connection with frames and plates of the aforesaid character and it pertains also to improvements in means by which the association of such index cards with retaining elements on frame members may be facilitated.

In printing devices of the aforesaid character it has been customary in the past to form a frame member, for example, of sheet metal with up-standing lugs, clips, spring tongues and beads which overlie or abut against the edges of printing plates and index cards to retain them in proper association with the frame. Printing devices of the aforesaid character may include one or more separate printing plates and one or more index cards. Examples are the printing devices disclosed in the patents to Mohler, No. 1,812,894, patented July 7, 1931; Berthelsen, No. 1,929,472, patented October 10, 1933, and prior patents issued to the present inventor, such as, Patent No. 2,030,865, patented February 18, 1936; No. 2,080,417, patented May 18, 1937; No. 2,115,444, patented April 26, 1938, and No. 2,132,412, patented October 11, 1938.

In the aforesaid patents, cards and plates of various widths and in various combinations are detachably retained on frames of the aforesaid character by means of overhanging clips, spring tongues, and inturned beads formed from material of the frame which beads overlie a margin of a plate and a margin of an index card.

In devices of the aforesaid character, it is frequently necessary to change plates and to change index cards to correspond with changes made in the plates. Inasmuch as these devices are used in large numbers a great deal of time is consumed in making the necessary changes and in inserting new plates and cards into frames.

It is, therefore, an object of the present invention to improve the design of index cards and to relate such design to the location and form of card retaining devices on frames of the aforesaid character so as to make it easier to assemble cards with retaining devices on such frames.

A further object of my invention is to design retaining elements on a frame and cooperating elements on the index card so as to provide for the efficient assembly and retention of cards by such retaining devices.

Another object of my invention is to design an index card in such a manner that it may be dis-

torted for application to a frame without causing injury to the card or without substantially reducing the degree of security with which the card is retained on the frame.

Other and further objects of the present invention will be apparent from the following description and claims and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a plan view of a printing device embodying my invention;

Fig. 2 is a plan view of an index card used in connection with the printing device shown in Fig. 1; and

Fig. 3 is a perspective view showing the manner in which the card shown in Fig. 2 may be applied to a printing device of the character shown in Fig. 1.

Referring first to Fig. 1, there is disclosed a printing device of the general character shown in the aforesaid patents to Mohler, Berthelsen and my prior Patents Nos. 2,030,865 and 2,080,417. In general, the printing device D shown in Fig. 1 embodies a frame of sheet material, preferably sheet metal, having an inturned bead along what may be termed the lower edge thereof shown at LB and an inturned upper bead UB along what may be called the upper edge of the frame. In addition to these beads, the frame shown in Fig. 1 has a plurality of lugs L1, L2 and L3 struck upwardly from the body thereof and bent to form overhanging retaining devices respectively for printing plates P1 and P2 and an index card C. To prevent movement of the printing plates P1 and P2 lengthwise between the retaining lugs which hold them against the frame, depressible spring tongues ST1 and ST2 are provided adjacent the respective ends of the frame, as is well understood in the art and described in detail in the aforesaid prior patents. The plates P1 and P2 are preferably of sheet metal having embossed printing characters thereon which are not shown herein but are also well known in the art.

The lower plate P2 is retained on the frame by the cooperation of the lower bead LB and the clips or lugs L1 which overhang the upper edge

of such plate. The upper plate P_1 is retained by clips or lugs L_2 , and as previously noted and well understood in the art the retaining devices ST_1 and ST_2 which are spring tongues struck from the body of the frame are arranged in this instance to permit insertion of either plate from either end of the frame serving normally however to restrict the plates against longitudinal movement but being readily compressible to permit removal of a plate and insertion of a new one whenever a change becomes necessary. Although I have shown an arrangement wherein two plates are associated with a frame, it will be understood that only one plate may be used, or three or more plates may be used if desired, the retaining devices being suitably arranged. This is well known in the art and forms no part of the present invention.

In order that the card C may bear data corresponding to the printing plates it is necessary, as well understood in the art, that the card be changed whenever a plate to which it is related is changed, that is, if any alteration in subject matter is required on the card. As shown in Fig. 1 and also as shown in the prior patents mentioned above, index cards, such as C , are retained in assembled position with the frame and in spaced relation with respect to the printing plate or plates by the overhanging upper bead UB and the clips or lugs L_3 . More than one index card might be used; a card for example might be placed in the general area occupied by Plate P_1 , the necessary retaining means being suitably modified. However, the present form of my invention is particularly concerned with the card C which is retained at least in part by the upper bead UB .

Inasmuch as index cards, such as C , are normally made of paper and are easily torn, as when printing devices of this character are slid one over another, it is desirable that the card be retained closely against the surface of the frame so as to be less likely to be caught and damaged by projecting elements, as on other printing devices D . For this reason, the bead UB and the lugs or clips L_3 usually closely overlie the card and assembly of such card with the frame involves sliding it along under these retaining devices. As indicated in the upper right corner of Fig. 1 the upper bead preferably has a part R_1 which is flared or raised slightly higher than the remainder of the bead to facilitate insertion of a card thereunder so that the card can be slid along into position against a retaining clip or lug 11 at the left end of the frame, as seen in this figure. Another retaining clip or lug 12 is provided at the right end, as viewed in Fig. 1, of the area to be occupied by the card C and this lug is preferably spaced from the lug 11 a distance very slightly greater than the length of a card C to allow for expansion only, so that when the card is assembled with the frame it will be closely retained against endwise movement. The clips 11 and 12 preferably comprise substantially vertical portions 13 against which the ends of the card C may abut, and bent overhanging portions 14 which overlie the end portions and tend to hold them flat against the surface of the frame. The frame F of printing device D is preferably perforated as described in a copending application by Carl J. Hueber, Serial No. 583,050, filed March 16, 1945, now issued as Patent No. 2,456,943, patented December 21, 1948. These perforations are indicated at 20 , Figs. 1, 3, and 5, and the card may be perforated opposite any one of said per-

forations to perform a control function. Hence it is desirable that the card C or C_1 be accurately located on the frame.

With cards of the type used in prior art, the assembly of a card with a frame involved considerable difficulty inasmuch as the closely overlying bead UB and the cooperating lugs L_3 made it difficult to compress the card in length sufficiently to insert the trailing end thereof under the overhanging retaining lug 12 . Hence, in attempting to insert cards of the aforesaid character into frames provided with retaining devices, as just described, many cards have been damaged and considerable difficulty in assembly has been experienced with consequent added expense and loss of time.

In order to overcome the difficulties just mentioned above I provide a card C of modified form having a portion of one edge cut away so as to clear retaining devices which otherwise would prevent buckling of the card. Thus, as shown in Fig. 2, an intermediate portion of the upper margin of the card C is cut away to a width sufficient to clear the bead UB and for a length along the margin sufficient to permit upward buckling of a part of the card C when forces tending to shorten said card are applied thereto. Hence, when the card is slid lengthwise of the retaining devices against the retaining member such as lug or clip 11 , further pressure applied against the trailing end of the card, at the right, as seen in Figs. 1 and 2, tending to push the card further to the left, causes the cut away portion of the card to buckle and rise above the bead UB . This condition is shown in Fig. 3. It should be particularly noted that the cut away portion which I have indicated by the reference character 35 is disposed at a point along the edge of the card C where no retaining device, such as L_3 , is arranged for cooperation at a directly opposing point on the lower edge of the card. By this construction, buckling of the card is easily accomplished and this is done by continuing to push on the trailing end of the card C after the advance end thereof, shown at the left in the drawings, has been stopped by the retaining clip or lug 11 . Pushing is continued until the trailing end of the card clears clip or lug 12 and the card is buckled as shown in Fig. 3. Inasmuch as the degree of buckling required to clear the overhanging elements 14 of the lug 12 is not very great the inherent resilience of the stock of which card C is made is sufficient to restore it to its normal flat condition where it lies against the frame without any appreciable permanent deformation. Hence, although the card is designed to be thus buckled on insertion the effect of this buckling is not retained in the card after assembly with the frame and no difficulty of the character mentioned above is likely to result from catching of the card on parts of other printing devices. It will of course be understood that the cut out portion may be formed at various locations along the upper edge of the card C and that the card might be inserted from the left as well as from the right as seen in Figs. 1 and 3. It should be particularly noted that the cut away portion 35 of the card C is not formed, located or designed for clearing a retaining device by merely sliding the card to a position clear of such device. In the present invention, the portion 35 has a specific form and purpose to clear a part of the continuous upper bead UB which obviously

could not be accomplished by merely displacing the card C to the right or to the left.

It will also be understood that my invention might be used with various types of printing devices such as those shown in the aforesaid patents or modifications thereof, having various arrangements of printing plates and cards thereon. In particular my invention might be applied, if desired to printing devices utilizing thin edged printing plates and low overlying retaining devices therefor, as disclosed for example in the copending application filed by Carl J. Hueber, Serial No. 450,320, filed July 9, 1942, now issued as Patent No. 2,425,323, patented August 12, 1947.

Hence, while I have illustrated and described the preferred embodiment of my invention, it is to be understood that this is capable of variation and modification and I, therefore, do not wish to be limited to the precise details set forth, but desire to avail myself of such changes and alterations as fall within the purview of the following claims.

I claim:

1. In a printing device, a rectangular frame made from sheet metal and embodying means for securing a printing plate thereon and also including card-mounting means defining a rectangular card receiving area and comprising a reversely bent retaining bead extended along one edge of said frame to afford a continuous overhanging card retaining member along one side of said area, overhanging retaining clips at opposite ends of said area, and a plurality of other overhanging retaining clips disposed along the opposite side of said area with a substantial space between at least two of said other clips, and an index card of flexible and resilient sheet material of a form corresponding substantially with said area and affording first and second side edges adapted to be positioned respectively beneath said retaining bead and said other clips and having a portion of said first side edge cut away opposite one of said spaces between said other clips so as to enable said card to be buckled momentarily in an endwise direction and upwardly past said bead to thereby reduce the effective length of the card and enable the same to be inserted under the overhanging clips at the ends of said area.

2. In a printing device that has a rectangular frame made from sheet metal and embodies means for securing a printing plate thereon and also includes card-retaining means defining a rectangular card receiving area and comprises a reversely bent retaining bead extended along one edge of said frame to afford a continuous overhanging card retaining member along one side of said area, overhanging retaining clips at opposite ends of said area, and a plurality of other overhanging retaining clips disposed along the opposite side of said area with a substantial space between at least two of said other clips, the combination of an index card being made from flexible and resilient sheet material of a form corresponding substantially with such area and affording first and second side edges adapted to be positioned respectively beneath such retaining bead and such other clips and having a portion of said first side edge cut away in a position arranged to be opposite one of such spaces between such other clips so as to enable said card to be buckled momentarily in an endwise direction and upwardly past such bead to thereby reduce the effective length of the card and enable the same to be inserted under the overhanging clips at the ends of such area.
